ATTORNEY

UNITED STATES PATENT OFFICE.

RICHARD BAER, OF NEW YORK, N. Y.

CONTAINER SEAL.

1,419,912.

Specification of Letters Patent. Patented June 20, 1922.

Application filed January 10, 1921. Serial No. 436,056.

To all whom it may concern:

Be it known that I, RICHARD BAER, a citizen of Czechoslovakia, and resident of the borough of Manhattan, in the city, county, and State of New York, have invented certain new and useful Improvements in Container Seals, of which the following is a specification.

This invention relates to an improved bottle seal and has for its primary object to provide a sealing device for bottles or other containers which may be easily and quickly applied to the outlet of the container to securely seal the same and as readily removed therefrom.

The invention further contemplates the provision of a container seal designed to be repeatedly used and which is of such construction that the various parts of the device are at all times permanently connected or associated and the possibility of their loss thus precluded.

It is also the purpose of my present improvement to provide a device of the above character which can be very cheaply manufactured and sold at nominal retail cost to the individual.

With the above and other objects in view, the invention consists in the improved form, construction and relative arrangement of the several parts as will be hereinafter more particularly described, illustrated in the accompanying drawing and subsequently incorporated in the subjoined claims.

In the drawing wherein I have illustrated one satisfactory and preferable embodiment of the invention and wherein similar reference characters designate corresponding parts throughout the several views:

Figure 1 is a vertical sectional view through the seal showing the same applied to the neck of a bottle or container.

Figure 2 is a side elevation, and

Figure 3 is a top plan view.

Referring in detail to the drawing, in the illustrated embodiment of my invention I provide a yoke shaped body 5 formed from a metal strip of requisite width and more or less resilient. One end of this metal strip is permanently connected as at 6 to the medial portion of a split spring metal band or ring 7. The ends of this band 7 are laterally extended closely adjacent to each other to provide latch dogs 8 having beveled end edges 9. These latch dogs are adapted for engagement through a slot 10 formed in the free

end portion of the body strip 5. Each of said dogs is provided in its lower edge with a notch or recess 11 to receive the lower end edge of the slot 10, as clearly shown in Figure 1 of the drawing.

The extremity of the metal body strip 5 is bent upon itself as at 5' and downwardly turned to afford a suitable finger piece.

A clamping screw 12 is threaded in a boss 65 or enlargement centrally formed upon the intermediate horizontal portion of the body strip 5. This screw at one end is provided with a head 12' adapted for bearing engagement upon the metal sealing cap 13. This 70 metal sealing cap has an uncorrugated or straight annular flange and within the same a disc of cork or other suitable material indicated at 14 is arranged. The other end of the screw 12 is formed with the thumb piece 75 15 by means of which said screw may be conveniently turned.

The cap 13 is permanently connected to the screw 12 by means of the angular metal strips 16, which are arranged in opposed relation to each other and extend upon the top of the cap 13 and the annular flange thereof, each of said strips being provided on one end with an inwardly turned lug 16' engaging over the edge of said flange. The latter end portions of the metal strips 16 may be welded or otherwise permanently fixed to the flange of the sealing cap. The other end portions of said strips are offset above the surface of the sealing cap and overlie the 90 head 12' on the clamping screw as indicated at 17, said offset ends being recessed to loosely surround the shank of the screw.

In the application and use of the device, the yoke shaped body strip 5 is arranged 95 with its arms extending longitudinally along diametrically opposite sides of the bottle neck B and in contact with the peripheral bead or enlargement b thereof. It will be noted that the end 6 of the body strip which 100 is permanently connected to the band 7 is bent inwardly so that it underlies the bead b. The band 7 thus clamps against the periphery of the bottle neck immediately beneath this bead. The other arm of the strip 105 5 is then forced inwardly and downwardly and engaged with the latch dogs 8 as shown in Figure 1. The screw 12 is then adjusted to force the sealing cap downwardly and tightly clamp the sealing disc 14 upon the 110 upper edge of the bottle neck around the outlet opening. As the cap is forced down-

wardly by the adjustment of the screw, the yoke 5 is, of course, pulled upwardly, thus causing the upper edge of the band 7 to be brought into tight frictional contact with 5 the underside of the bead 6. Consequently the device will be very firmly or securely fixed upon the bottle neck and its turning movement, which would tend to loosen the clamping screw, entirely obviated. In this 10 manner a very effective seal of the bottle is procured. The device can be readily detached or removed by simply loosening the screw and forcing downwardly on one arm of the yoke 5 to disengage said arm from 15 the latch dogs 8. When removed it will be observed that all parts of the device remain permanently connected so that they will not become misplaced or lost. By means of a sealing device of this nature, a portion of 20 the contents of the bottle may be decanted and the sealing cap then readily replaced to again effectually seal the bottle.

From the foregoing description considered in connection with the accompanying drawing, it will be seen that I have produced a 25 sealing device for bottles and other containers of very simple and inexpensive construction and which is admirably adapted for house-hold use. While I have referred to 30 the seal as primarily designed for use in connection with bottles for containing beverages, it will be apparent that by resorting to obvious structural modifications, the device may also be employed with equal efficiency upon jars or other forms of 35 containers. It is, therefore, to be understood that while I have herein illustrated one practical embodiment of my improved container seal, the device is nevertheless susceptible of 40 exemplification in many other alternative constructions and I reserve the privilege of adopting all such legitimate changes in the form, construction and arrangement of the several parts as may be fairly embodied in 45 the spirit and scope of the invention as claimed.

I claim:

1. A container seal comprising a band 50 adapted to be passed about the container below the mouth thereof and to engage with a portion of the container to avoid movement toward said mouth, said band having its free ends out-turned and lying in substantially parallel planes, a yoke having one end 55 engaged with the intermediate portion of the band and adapted to extend across the mouth of the bottle, the other end of the yoke being slotted and closed at the sides of the slot, said slot adapted to engage about 60 the parallel out-turned ends of the band, said slotted end portion of the yoke and the out-turned end of the band having co-oper-

ating interlocking means, a cap for the bottle mouth, and means held by the yoke for pressing the cap against the bottle mouth. 65

2. A seal for bottles and the like comprising a resilient band adapted to be placed about a bottle neck beneath an outstanding bead thereon and having its free end portions outturned and arranged to be brought 70 into proximity to each other and having undercut notches in their lower edges, a yoke strip secured at one end to the median portion of said band and arranged to extend upwardly about said bead and over the top 75 of the bottle neck, said yoke strip having a slot in its free end portion adapted to receive the outturned ends of the band therethrough and the lower edge of the slot being adapted 80 to engage the notches in the ends of the band for interlocking the parts together, said yoke strip having its free end bent outwardly 85 to form a cam face and a finger held to the outer edge portions of said ends of the band having beveled faces adapted to guide the yoke strip into its interlocking relation with the band, and a cap carried upon the yoke strip adapted to close the top of the bottle neck.

3. A container seal comprising a thin flat 90 metallic band adapted to encircle the container at a distance below the mouth thereof and adapted to be held against movement toward the mouth, said flat band having free out-turned ends lying side by side in substantially parallel planes, the under edges of the out-turned ends being provided with registering notches, a yoke having one end 95 engaged with the intermediate portion of the band and extending across the mouth of the 100 bottle, the other end of the yoke being provided with a slot being closed about all its edges and adapted to be received over the out-turned ends of the band and having the portion beneath the slot adapted to extend 105 into said notches, a cap for the container mouth, and presser means carried by the yoke for operating against the cap.

4. A container seal comprising a band 110 passing about the container near the mouth, a yoke connected to the band and extending across the mouth of the container, a cap on the container, a screw held by the yoke and having a head band against the cap, and angle strips welded to the cap and having 115 overturned ends engaged beneath the edges of the cap, said strips further having offset inner ends engaging freely upon the screw head.

In testimony that I claim the foregoing 120 as my invention, I have signed my name hereunder.

RICHARD BAER.
